LUGGAGE HANDLE

Sab Finkelstein, Glenside, Pa., assignor to Philadelphia
Brief Case Company, Philadelphia, Pa., a partnership

Application January 26, 1959, Serial No. 54,302

Term of patent 14 years

(Cl. D87—2)

Fig. 1

Fig. 2

Fig. 3

I claim:

The ornamental design for a luggage handle, substantially as shown.
